UNITED STATES PATENT OFFICE

IRA D. STARCHER AND CHARLES E. YOUNG, OF SWANDALE, WEST VIRGINIA.

BARREL-STAVE-CUTTING MACHINE.

Application filed October 12, 1921. Serial No. 507,320.

To all whom it may concern:

Be it known that we, IRA D. STARCHER and CHARLES E. YOUNG, citizens of the United States, residing at Swandale, in the 5 county of Clay and State of West Virginia, have invented certain new and useful Improvements in Barrel-Stave-Cutting Machines, of which the following is a specification, reference being had to the accompanying drawings.

The present invention has for its purpose the provision of a machine, whereby the opposite edges of the barrel stave are arcuately formed and beveled simultaneously, so that when the staves are brought together to form a barrel, they will uniformly and accurately fit.

Another purpose is to provide a machine of this character, wherein the barrel staves 20 are made uniformly, so that the staves will properly fit, and all barrels made of the same number of staves, will be of a uniform diameter in cross section, as well as being of a uniform shape.

Another purpose is the provision of a machine which will cut staves of any width by operating a hand-wheel which causes the 25 saws to be adjusted either inwardly or outwardly to make either narrow or wide staves.

Still another purpose is the provision of a carriage, including a bed above the carriage on which the stave is guided, in combination with a spring tensioned stave engaging claw protruding above the bed, to 30 assist in holding the stave in position while being fed through the machine and thereby to cut the stave to the proper shape.

A further purpose is the provision of combined gravity and spring means for returning the carriage to its initial position, it being obvious that either the gravity or the 40 spring means may be dispensed with if desired.

A still further purpose is the provision 45 of a machine of this design wherein opposed circular saws are employed for cutting the opposite edges of the stave, the carriages of the saws being operatively connected with the feed carriage below the bed, so that when 50 the feed carriage is operated longitudinally of the frame of the machine, the saw supporting carriages will move toward and from each other, whereby the opposite edges of the stave are given arcuate contours, so that 55 when a series of staves are put together, they will form the usual shape of a barrel.

The invention additionally aims to provide means for adjusting the saw supporting carriages toward and from each other, in order to vary the width of the stave. 60

The invention also aims to provide a bed including rollers for the barrel staves, and superimposed opposite rollers bearing upon the staves during their passage between the rollers, to hold and guide them while being 65 cut.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the 70 scope of what is claimed.

The invention comprises further features and combination of parts, as will be hereinafter set forth, shown in the drawings and claimed.

In the drawings:

Figure 1 is a view in side elevation of the improved barrel stave cutting machine constructed in accordance with the invention;

Figure 2 is a vertical longitudinal sectional view through the same;

Figure 3 is a plan view;

Figure 4 is a sectional view on line 4—4 of Figure 1;

Figure 5 is a transverse sectional view on line 5—5 of Figure 2;

Figure 6 is a sectional view on line 6—6 of Figure 1, looking upwardly in the direction of the arrow, thereby showing the various parts of the machine in bottom plan; and

Figure 7 is a detail view of one of the pulleys 73.

Referring to the drawings, 1 designates the frame, which may be of any suitable shape or construction, preferably rectangular as shown. The upper part of the frame comprises a bed consisting of the side rails 2 and the intermediate bed rails 3, and mounted in bearings 4 and 5 of the side and intermediate rails are shafts 6, on which 100 stave bed rollers 7 are mounted to rotate therewith. These rollers are interposed between the intermediate rails 3 of the bed, and are designed to support the stave as it is being cut. Preferably the bed has eight 105 rollers, though it is obvious that any number of rollers may be employed, preferably 110

four in front and four to the rear. A corresponding number of opposed stave holding rollers 8 are superimposed relatively to the rollers 7, and are mounted upon the 5 shafts 9. These shafts 9 are mounted in bearings of the links 10, which are pivotally mounted upon the shafts 11, as shown clearly in Figures 1, 2 and 3. The shafts 11 are mounted in bearings 12, which rise 10 from the longitudinal side rails 2. The shafts 9 have sprockets 13, which are connected by chains 14 to the sprockets 15, which are carried by and are rotatable with the shafts 11. Certain ends of the shafts 11 15 have sprockets 16, about which sprocket chains 17 engage. The sprocket chains 17 in turn engage sprockets 18 upon stub shafts 19, which are mounted in bearings of the under side of one of the upper longitudinal 20 side rails 2 and one of the intermediate rails 3. Additional sprockets 20 are mounted upon the stub shafts 19 and are engaged by the sprocket chains 21, which operatively gear with the sprockets 22, which are 25 mounted upon the shafts 6. It will be noted that one of the shafts 6 is in two sections 6^a, which are axially aligned, and have their adjacent ends separated to permit the passage of a stave engaging claw 23. An additional sprocket 24 is carried by one of 30 the shafts 6, adjacent the feed end of the machine, said sprocket being engaged by a sprocket chain 25. One end of one of the sections 6^a of one of the shafts 6 has an 35 additional sprocket 26, about which a sprocket chain 27 travels. The corresponding end of the opposite section 6^a has a sprocket 28 engaged by a sprocket chain 29, which engages about a sprocket 30 on the 40 shaft 6 which is adjacent the far discharge end of the machine. Mounted in bearings of the lower longitudinal side rails 31 of the frame is a drive shaft 32 carrying a pulley 33, to which any suitable power (not shown) 45 may be belted. Also mounted upon the drive shaft 32 are sprockets 34 and 35. Also mounted in bearings of the lower side rails 31 of the frame are stub shafts 36, which carry sprockets 37, engaged by the 50 sprocket chains 28. The sprocket chains 38 engage about the sprockets 34 and 35, so that power may be transmitted from the drive shaft 32 to the stub shafts 36, and since the chains 25 and 27 engage about the 55 sprockets 39 which are also mounted upon the stub shafts 36, power is transmitted to one of the shafts 6 and one of the shaft sections 6^a. Obviously since the shafts 6 and the shaft sections 6^a are connected as previously described, power is transmitted to the bed rollers, and from the bed rollers to the stave holding rollers 8, in order to feed the staves through the machine.

Obviously the bed rollers and the stave holding rollers may be rubber covered (not

shown) or otherwise provided with feeding surfaces (not shown) in order to insure feeding the stave through the machine.

A channel guide 40 is mounted upon the lower end rails 41 of the frame, the channel 70 of which is T-shaped in cross section, and receives a correspondingly shaped carriage 43, the lower surface of which has suitable rack teeth 44, which are engaged by the teeth of the gear 45, which is mounted upon 75 a shaft 46 in bearings 47 of the channel guide. This shaft is also mounted in bearings of one of the longitudinal side rails of the frame, and surrounding the shaft is a coil spring 48, one end of which is attached 80 at 49 to the frame of the machine, while the other end is attached at 50 to the shaft, so that when the carriage 43 is moved forward, the spring 48 will tend to turn the shaft and gear 45 in the direction to return the carriage 85 to its initial position.

It will be noted that the carriage 43 is elongated, and carried thereby are two parallel strips 51, which are provided with a plurality of apertures or openings 52. A 90 pin 53 is designed to engage through any two registering openings or apertures 52, and through the stave engaging claw 23, in order to pivotally and adjustably mount the claw on the carriage 43. This claw 23 engages and operates between the innermost intermediate rails 3 of the frame, and is provided with a serrated claw shoulder 54, which normally protrudes upwardly beyond the upper surface of the top rails of the 100 frame, in order to be engaged by the stave 55 to be cut. The claw 23 has a forward cam edge 56, which, as the carriage 43 reaches the limit of its movement, engages and cams upon the shaft 6 adjacent the discharge end of the frame, thereby camming the claw downwardly against the action of its leaf spring 57, and thereby disengaging the shoulder 54 from the end of the stave. Obviously the claw may be adjusted to accommodate barrel staves of different lengths. 110

The end portions of the carriage 43 are provided with transversely disposed guide rails 58, on which the saw carriage moving plates 59 are guided. These saw carriage moving plates have arcuate slots 60, in which the feet 61 of the saw carriages are movable. In other words the saw carriage operating plates 59 are movable longitudinally of the frame, and since the slots 60 are 115 arcuate in contour, the feet are given a slight rocking movement in a horizontal plane. The feet 61 are secured by bolts 62 to the depending legs 63, which are carried by the saw carriages 64, which are movable laterally toward and from each other in guides 64^a. In fact the upper parts of the legs 63 have cylindrical portions 65, which will rotatably engage correspondingly shaped openings 66 of the saw carriages. 120 125 130

Beyond the cylindrical portions 65, the legs 63 have extensions 67 rectangular in cross section, which engage correspondingly shaped openings 68 in the bases of the mandrel holding blocks 69. It will be noted that the legs 63 are movable rockably relatively to the saw carriages 64, and are movable with the bases of the mandrel holding blocks 69; therefore when the feet and legs 61 and 10 63 rock according to the shape of the arcuate slots 60, the mandrel holding blocks 69 will correspondingly move, so that the circular saws may twist in a plane horizontally.

Mandrels 70 are mounted in bearings 71 of the mandrel holding blocks 69 and carry circular saws 72. It will be noted that the mandrels 70 are inclined downwardly and laterally from each other, so as to hold the circular saws at angles converging downwardly and toward each other. By this arrangement the saws act to bevel the stave, so that the stave may fit and engage with adjacent staves, in forming the barrel.

The mandrels carry pulleys 73, which are 25 engaged by the round belts 74, which pass over the idlers 75, and also engage the groove pulleys 76, which are mounted upon the drive shaft 32, therefore it will be noted that when power is transmitted to the shaft 32, motion is imparted to the mandrels 70, thereby rotating the circular saws. A suitable guard 77 is provided, so as to protect the operator's hands from the teeth of the saws. Also mounted upon the bases of the 35 mandrel supporting blocks 69 are suitable guides or guards 78, which are provided for the purpose of preventing excessive vibrations of the saws.

The rectangular extensions 67 receive 40 transversely disposed pins 79, which are positioned above the bases of the mandrel supporting blocks, and thereby act to prevent downward movements of the legs.

It will be noted that the plates 59 are 45 movable transversely of the machine, and since they are guided upon the guides 58, which are carried by the carriage 43, the plates 59 are held in their relative positions. However, the lower faces of the 50 plates 59 have grooves 80, which are engaged by the lugs 81 of the racks 82, which in turn mesh with the gears 83, mounted upon the shafts 84 and 85. The far end of the machine has a transverse shaft 86 55 mounted in bearings 87, and carried by the shaft 86 are beveled gears 88, which mesh with the bevel gears 89 carried upon the shafts 84 and 85. One end of the shaft 85 has a hand wheel 90, by which motion may 60 be imparted to the shaft 85, and through the medium of the shaft 86, motion is imparted to the shaft 84. By this arrangement it is obvious that the plates 59 may be adjusted toward and from each other, and in so doing, 65 the saw carriages 64 may likewise be adjust-

ed, thereby positioning the circular saws closer together or farther apart, for the purpose of making wide or narrow staves, according to the size of barrel to be constructed. The gears 83, are mounted between the 70 bearings 91, in which the shafts 84 and 85 are mounted.

Each of the plates 59 comprises a body section 92 and a clamping section 93, which is detachably secured by bolts 94 to the body 75 section, whereby the clamping section 93 may be detached, for the purpose of grinding its faces 95, so as to position the arcuate face 96 of the clamping section closer to the opposite arcuate face of the slot 60. In 80 other words the opposite arcuate faces of the slots 60 in time become worn, and in order to compensate for the wear, the clamping sections 93 may be detached, so that the faces 95 of the clamping sections 93 and the corresponding faces engaged by the faces 95 may be ground or machined, so that when the clamping sections 93 are reconnected to the body sections, the slots 60 are made narrower, sufficient to properly receive the 90 feet 61.

In the operation, the piece 55 from which a stave is to be cut is placed so as to pass between the rollers 8 and the rollers 7, so that the end of the piece may engage the 95 claw shoulder 54, and then the pressure is applied to the piece or strip 55, pushing the claw 23 forward and with it the carriage 43, and since the plates 59 are operatively connected to the carriage 43, the plates 59 100 correspondingly move, and since the slots 60 are of arcuate contour, rocking movements are imparted to the feet and the legs 61 and 63, thereby correspondingly rocking the mandrel carrying blocks 69. Obviously 105 the saws 72 will rock in horizontal planes, according to the shape of the arcuate slots 60, and will thereby cut a stave of proper shape, to cooperate with similar staves, when forming a barrel. It will be noted that the 110 saws 72 converge downwardly and toward each other, and owing to this arrangement the opposite longitudinal edges of the stave are beveled simultaneously with the arcuate shape given to said edges, so that when the 115 staves are arranged in position to form a barrel, they will properly fit, in order to render the barrel of circular contour in cross section.

When the stave has finished its travel 120 through the machine, and the teeth of the saws have completed their work, the inclined cam edge 56 contacts with the shaft 6 adjacent the forward portion of the frame of the machine, which will cause the claw 23 to cam downwardly against the action of the leaf spring 57. As soon as the stave disengages from the claw shoulder 54 the claw may return to its initial position under the action 125 of the spring 57. At the same time that 130

the claw is returned to its initial position, the carriage 43 is returned to its normal position, through the medium of the spring 48 and the weight 97, which is attached to a suitable cable or rope 98, which in turn is connected at 100 to the carriage 43. The cable or rope 98 passes over a pulley 101, which may be mounted in any suitable manner upon a stationary structure (not shown) 10 to the rear of the machine.

Coil springs 102 surround the shafts 11. One end of each coil spring 102 is attached at 103 to one of the arms 10, while its other end is attached at 104 to the diametrically 15 opposite arm 10. The construction and arrangement of these springs 102 are such as to exert pressure on the arms, so as to hold the rollers 8 upon and in contact with the stave or the piece from which the stave is 20 cut, during its passage through the machine.

The grooves in the pulleys 73 and 76 are relatively deep and wide, and their flanges flare outwardly. In other words the walls of the grooves flare outwardly, particularly 25 those of the pulleys 73, as shown in Figure 7, so as to prevent the round belts 74 from slipping off.

The invention having been set forth, what is claimed is:

30 1. In a stave cutting machine, a frame, upper and lower feed rollers for the stave, a carriage with which the stave operatively connects for feeding said carriage with the stave, laterally movable mandrel holding 35 blocks, circular saws carried thereby, and means operatively connecting said carriage and the blocks, to impart rocking movements to the blocks, whereby rocking movements may be imparted to the circular saws to vary 40 their cutting planes.

2. In a stave cutting machine, a frame, opposed mandrel holding blocks mounted for rocking movements in horizontal planes upon the frame, circular saws operatively 45 mounted upon said blocks, a carriage with which a strip for forming a stave operatively connects, and means operatively connecting the carriage and the blocks for imparting rocking movements to the latter to 50 rock the saws to vary their cutting planes for cutting a barrel stave with opposite arcuate edges.

3. In a stave cutting machine, a frame, opposed mandrel supporting blocks mounted for rocking movements in horizontal planes upon the frame, circular saws operatively mounted upon the mandrel supporting blocks, means for carrying a strip under and between the saws, means operated there- 60 by for rocking said blocks, whereby the saws may rock to vary their cutting planes and cause them to cut a stave with opposite arcuate edges.

4. In a stave cutting machine, a frame, 65 opposed mandrel supporting blocks mounted

for rocking movements in horizontal planes upon the frame, circular saws operatively mounted upon the mandrel supporting blocks, means for carrying a strip under and between the saws, means operated thereby for rocking said blocks, whereby the saws may rock in horizontal planes to vary their cutting planes and cause them to cut a stave with opposite arcuate edges, said last named means including an adjustably mounted claw with which the strip from which the stave is cut engages. 75

5. In a stave cutting machine, a frame, opposed mandrel supporting blocks mounted for rocking movements in horizontal planes upon the frame, circular saws operatively mounted upon the mandrel supporting blocks, means for carrying a strip under and between the saws, means operated thereby for rocking said blocks, whereby the saws may rock to vary their cutting planes and cause them to cut a stave with opposite arcuate edges, said means including a yieldably mounted claw, with which the piece from which the stave is to be cut engages, 80 and means for disengaging said claw. 85

6. In a stave cutting machine, a frame, opposed mandrel supporting blocks mounted for rocking movements in horizontal planes upon the frame, circular saws operatively mounted upon the mandrel supporting blocks, means for carrying a strip under and between the saws, means operated thereby for rocking said blocks, whereby the saws may rock to vary their cutting planes and cause them to cut a stave with opposite arcuate edges, said means including an adjustably mounted claw with which the piece from which the stave is to be cut engages, 90 means for camming the claw out of engagement with the stave, as the stave passes through the machine, and means for returning the claw to its initial position. 95

7. In a stave cutting machine, a frame, opposed mandrel supporting blocks mounted for rocking movements in horizontal planes upon the frame, circular saws operatively mounted upon the mandrel supporting blocks, means for carrying a strip under and between the saws, means operated thereby for rocking said blocks, whereby the saws may rock in horizontal planes to vary their cutting planes and cause them to cut a stave with opposite arcuate edges, said means including an adjustably mounted claw with which the piece from which the stave is to be cut engages, said claw having a stave engaging claw shoulder, means for camming the claw downwardly, thereby disengaging the claw shoulder from the stave, and means for returning the claw to its initial raised position. 100

upon the frame, said blocks being capable of movements toward and from each other, circular saws operatively mounted upon the blocks, means with which a strip from which 5 a stave is to be cut operatively engages, said means being operatively connected with said blocks, whereby they may rock, correspondingly moving the saws to vary their cutting planes, and means for adjusting the blocks 10 toward and from each other, whereby staves of different widths may be cut.

9. In a stave cutting machine, a frame, opposed mandrel supporting blocks mounted for rocking movements in horizontal planes 15 upon the frame, said blocks being capable of movements toward and from each other, circular saws operatively mounted upon the blocks, means with which a strip from which a stave is to be cut operatively engages, said means being operatively connected with said blocks, whereby they may rock, correspondingly moving the saws to 20 vary their cutting planes, and means for adjusting the blocks toward and from each other, whereby staves of different widths 25 may be cut, and means for returning the first mentioned means to its initial position.

10. In a stave cutting machine, a frame, opposed mandrel supporting blocks mounted for 30 rocking movements in horizontal planes upon the frame, said blocks being capable of movements toward and from each other, circular saws operatively mounted upon the blocks, means with which a strip from which 35 a stave is to be cut operatively engages, said means being operatively connected with said blocks, whereby they may rock, correspondingly moving the saws to vary their cutting planes, and means for adjusting the blocks 40 toward and from each other, whereby staves of different widths may be cut, and means for returning the first mentioned means to its initial position, said means including a stave 45 engaging claw, and means for camming the claw out of engagement with the stave prior to the returning of said first mentioned means to its initial position.

11. In a stave cutting machine, a frame, mandrel supporting blocks mounted for 50 rocking movements in horizontal planes upon the frame, saws mounted upon said blocks, a longitudinally movable carriage including a stave engaging claw, upper and lower guide rollers for carrying the stave 55 through the machine, auxiliary carriages movable with the first named carriage and provided with arcuate slots, and means operatively fixed to the mandrel carrying blocks, so as to rock therewith, and operatively engaging said arcuate slots of the auxiliary carriages, whereby the mandrel carrying blocks may rock in horizontal planes, thereby correspondingly rocking the saws to 60 vary their cutting planes and give the stave opposite arcuate edges, the construction and arrangement of the mounting of the circular saws being such as to bevel the arcuate edges of the stave simultaneously with the cutting 65 thereof, and means for adjusting the man-

12. In a stave cutting machine, a frame, mandrel supporting blocks mounted for rocking movements in horizontal planes upon the frame, saws mounted upon said blocks, a longitudinally movable carriage including a stave engaging claw, upper and lower guide rollers for carrying the stave through the machine, auxiliary carriages movable with the first named carriage and provided with arcuate slots, and means operatively fixed to the mandrel carrying blocks, so as to rock therewith, and operatively engaging said arcuate slots of the auxiliary carriages, whereby the mandrel carrying blocks may rock in horizontal planes, thereby correspondingly rocking the saws to 70 vary their cutting planes and give the stave opposite arcuate edges, the construction and arrangement of the mounting of the circular saws being such as to bevel the arcuate edges of the stave simultaneously with the cutting thereof.

13. In a stave cutting machine, a frame, mandrel supporting blocks mounted for rocking movements in horizontal planes 90 upon the frame, saws mounted upon said blocks, a longitudinally movable carriage including a stave engaging claw, upper and lower guide rollers for carrying the stave through the machine, auxiliary carriages 95 movable with the first named carriage and provided with arcuate slots, and means operatively fixed to the mandrel carrying blocks, so as to rock therewith, and operatively engaging said arcuate slots of the auxiliary carriages, whereby the mandrel carrying blocks may rock in horizontal planes, thereby correspondingly rocking the saws to 100 vary their cutting planes and give the stave opposite arcuate edges, means for adjusting the mandrel holding blocks toward and from each other, to vary the width of the stave.

14. In a stave cutting machine, a frame, mandrel supporting blocks mounted for 110 rocking movements in horizontal planes upon the frame, saws mounted upon said blocks, a longitudinally movable carriage including a stave engaging claw, upper and lower guide rollers for carrying the stave through the machine, auxiliary carriages 115 movable with the first named carriage and provided with arcuate slots, and means operatively fixed to the mandrel carrying blocks, so as to rock therewith, and operatively engaging said arcuate slots of the auxiliary carriages, whereby the mandrel carrying blocks may rock in horizontal planes, thereby correspondingly rocking the saws to 120 vary their cutting planes and give the stave opposite arcuate edges, the construction and arrangement of the mounting of the circular saws being such as to bevel the arcuate edges of the stave simultaneously with the cutting 125 thereof, and means for adjusting the man-

mandrel holding blocks toward and from each other, for varying the width of the stave.

15. In a stave cutting machine, a frame, mandrel supporting blocks mounted for 5 rocking movements in horizontal planes upon the frame, saws mounted upon said blocks, a longitudinally movable carriage including a stave engaging claw, upper and lower guide rollers for carrying the stave 10 through the machine, auxiliary carriages movable with the first named carriage and provided with arcuate slots, and means operatively fixed to the mandrel carrying blocks, so as to rock therewith, and oper- 15 atively engaging said arcuate slots of the auxiliary carriages, whereby the mandrel carrying blocks may rock in horizontal planes, thereby correspondingly rocking the saws to vary their cutting planes and give 20 the stave opposite arcuate edges, means for returning the longitudinally movable carriage to its initial position, and means camming the claw out of engagement with the stave prior to the return of the longitudinal- 25 ly movable carriage to its initial position.
16. In a stave cutting machine, a frame, mandrel supporting blocks mounted for rocking movements in horizontal planes upon the frame, saws mounted upon said 30 blocks, a longitudinally movable carriage including a stave engaging claw, upper and lower guide rollers for carrying the stave through the machine, auxiliary carriages movable with the first named carriage and 35 provided with arcuate slots, and means operatively fixed to the mandrel carrying blocks, so as to rock therewith, and operatively engaging said arcuate slots of the

auxiliary carriages, whereby the mandrel carrying blocks may rock in horizontal 40 planes, thereby correspondingly rocking the saws to vary their cutting planes and give the stave opposite arcuate edges, means for imparting revoluble movements to the circular saws and being operatively connected 45 to the upper and lower rollers for imparting movements thereto.

17. In a stave cutting machine, a frame, mandrel supporting blocks mounted for rocking movements in horizontal planes 50 upon the frame, saws mounted upon said blocks, a longitudinally movable carriage including a stave engaging claw, upper and lower guide rollers for carrying the stave through the machine, auxiliary carriages 55 movable with the first named carriage and provided with arcuate slots, and means operatively fixed to the mandrel carrying blocks, so as to rock therewith, and operatively engaging said arcuate slots of 60 the auxiliary carriages, whereby the mandrel carrying blocks may rock in horizontal planes, thereby correspondingly rocking the saws to vary their cutting planes and give the stave opposite arcuate edges, means for 65 imparting revoluble movements to the circular saws and being operatively connected to the upper and lower rollers for imparting movements thereto, and means for adjusting the mandrel holding blocks toward and from 70 each other for varying the width of the stave.

In testimony whereof we hereunto affix our signatures.

IRA D. STARCHER.
CHARLES E. YOUNG.
